UNITED STATES PATENT OFFICE.

WILLIAM M. CHASE, OF ATLANTIC CITY, NEW JERSEY, ASSIGNOR TO BENJAMIN F. CHASE, OF ROANOKE, VIRGINIA.

ROOFING FABRIC.

Application filed June 16, 1921. Serial No. 478,015.

To all whom it may concern:

Be it known that I, WILLIAM M. CHASE, a citizen of the United States, residing at Atlantic City, in the county of Atlantic and State of New Jersey, have invented certain new and useful Improvements in Roofing Fabrics, of which the following is a specification, reference being had therein to the accompanying drawing.

10 My invention relates to new and useful improvements in roofing fabric and has for its principal object the provision of such fabric having inturned longitudinal edges so that when the roofing is laid in strips the 15 inturned edges of adjacent strips may be interlocked, the edges being inturned prior to winding the fabric in rolls.

A further object resides in cutting the 20 ends of the strips of fabric in such a manner that they may be turned back to form tongues, between the inturned longitudinal edges, the tongues of the meeting ends of strips adapted to be interlocked for connecting the strips.

25 With the above and other objects in view, which will appear as the description proceeds, my invention consists of the novel details of construction and arrangement of parts, described in the following specification and illustrated in the accompanying drawings, and while I have illustrated and described the preferred embodiments of the invention, it will be understood that such changes may be made as will fall within the 30 scope of the appended claims.

In the drawings:

Figure 1 is a perspective of a roll of roofing fabric.

Fig. 2 is a fragmental top plan.

Fig. 3 is a longitudinal vertical section on the line 3—3 of Figure 2.

Fig. 4 is a transverse vertical section on the line 4—4 of Figure 2.

Fig. 5 is a fragmental transverse section 45 showing the manner of interlocking the adjacent strips of fabric, and

Fig. 6 is a transverse vertical section on the line 6—6 of Figure 2.

In the drawings, 1 indicates a strip of fabric of any desired construction adapted to be rolled, said fabric being coated with tar and covered, with the exception of a narrow strip along each longitudinal edge with

gravel or similar material, the uncovered edges being turned inwardly to form the 55 overlapping flanges 2. At each end the fabric is provided with the transversely spaced longitudinal slits 3, said slits forming the tongue 4 between the inturned flanges 2. The tongue 4 may be turned back over the 60 strip 1 so that the meeting ends of the strips may be connected by interlocking the tongues.

In applying the fabric to the roof, the strips are brought together, as clearly shown 65 in the drawings, with the inturned longitudinal flanges 2 of adjacent strips interlocking, nails 5 being driven through the flanges in the manner shown. It will be understood that both sides of the fabric are 70 coated with the tar and gravel with the exception of the inturned flanges so that either surface thereof may be exposed to the weather. When the strips are applied the nails are all covered as shown so that there 75 will be no chance of leaking at these points. When it is desired to connect the ends of the strips, the tongues 4 are bent back and interlocked and a nail may be driven there-through. As previously stated, the longitudinal edges will be turned inwardly before 80 the fabric is rolled and by doing this the fabric may be easily applied to the roof and the edges of adjacent strips interlocked. If desired any ornamental design may be 85 formed on the surface of the strips.

Having fully described my invention what I claim as new and desire to secure by Letters Patent is:

1. A roofing fabric covered with an asphalt composition on both faces with the exception of a relatively narrow strip along the longitudinal and transverse edges, all of said uncovered edges adapted to be folded over the body of the fabric to form members adapted 90 to be interlocked with adjacent strips of the fabric, the parallel faces of the inturned portions being disconnected from the covered portions of the fabric.

2. An article of manufacture comprising 100 a roll of roofing fabric covered with an asphalt composition on both faces with the exception of a relatively narrow strip along the longitudinal and transverse edges, both longitudinal uncovered edges being folded, 105 prior to rolling, over the body of the fabric

to form members adapted to be interlocked with adjacent strips of the fabric, the parallel face of the inturned portions being disconnected from the covered portion of the fabric.

3. A roofing fabric having both of its longitudinal edges folded inwardly over the body of the fabric, the parallel faces of the

inturned portions being disconnected from the body.

In testimony whereof I hereunto affix my signature in the presence of two witnesses.

WILLIAM M. CHASE.

Witnesses:

J. P. CAMPBELL,
GERTRUDE WEDEMEIER.
